EDWIN A. PARKER. OF HORSEHEADS, NEW YORK.

Letters Patent No. 77,519, dated May 5, 1868.

IMPROVEMENT IN COAL-STOVES.

The Schedule referred to in these Letters Patent and making part of the same.

TO ALL WHOM IT MAY CONCERN:

Be it known that I, EDWIN A. PARKER, of Horsheads, in the county of Chemung, and State of New York, have invented a new and improved Stove; and I do hereby declare that the following is a full, clear, and exact description thereof, which will enable others skilled in the art to make and use the same, reference being had to the accompanying drawings, forming part of this specification, in which—

Figure 1 represents a vertical longitudinal section of my improved stove, taken on the plane of the line xx , fig. 2.

Figure 2 is a horizontal section of the same, taken on the plane of the line yy , fig. 1.

Figure 3 is a vertical transverse section of the same, taken on the plane of the line zz , fig. 2.

Similar letters of reference indicate corresponding parts.

This invention relates to a novel manner of constructing the base of a stove or furnace, with a view of conducting a supply of fresh warmed air to the fire, to aid combustion, and of conducting another supply of fresh warmed air into the room, so that the air in the room will not only not be vitiated by the stove, but will actually be improved and purified by the constant stream of fresh warm air entering the room, a suitable ventilator being required to carry off the surplus air.

The present invention consists in arranging below the fire-box of the stove, and within the enlarged base of the same, a series of channels and chambers, which conduct air from the outside respectively into the fire-box and into the room, for the aforementioned purposes.

The invention also consists in carrying the products of combustion from the upper part of the stove down to the base, and into a chamber, in which an S-shaped partition is arranged, by which the said products of combustion are, when entering opposite sides of the base, caused to pass three-fourths around the base before they can reach the smoke-pipe; thereby the base is heated, so that it will warm the fresh air entering or passing through it.

A, in the drawing, represents a stove or furnace, of ordinary or suitable construction, fitted upon an enlarged base, B, and having a tubular downward-extending ash-box, C, as shown. The ashes and coal discharged from the grate D fall, through this tubular extension C, into any suitable receptacle or separator, that is arranged in a compartment below that in which the stove is set up.

In the base, B, is, by means of a partition, a , formed an annular channel, E, around the tube C, said annular channel extending down through or below the floor F, as shown; by having a tubular downward extension, b , on the base, which surrounds the tube C, and which is securely closed at the bottom.

The cover c of the channel E is perforated or fret-work, so that air from the said channel can pass, through these perforations, into the room.

The fresh air is admitted through a pipe, G, which may have a damper, to regulate the supply of air from the outside into the lower part of the channel E, in which it is partly heated by the surrounding warm base, and whence it may, through a hole, d , in the tube C, be conducted to the fire-box. The hole d is provided with a suitable valve or damper, e , by means of which the amount of air passing into the fire-box may be regulated. That portion of the base, B, which surrounds the channel E, is, by means of a horizontal partition, f , divided into two compartments, H and I, of which the lower one, H, communicates, by means of holes in the partition a , with the channel E; and, by means of holes, g , in its outer enclosure, with the atmosphere in the room.

Thus, whatever air is not carried to the fire-box through the hole d passes into the room, either through the holes c in the cover of the channel E, or through the perforations g in the outside of the chamber H.

The chamber I, being heated in a manner hereinafter set forth, serves to warm all the air passing through the channel E and chamber H, and thus a stream of warmed fresh air is not only conducted to the fire-box, but also, through the cover, to the outside of the stove, to mingle with the heated air radiating from the stove, and to purify the same, and, through the holes g , along the floor of the room, to warm the floor around the stove.

J is the smoke-pipe, through which the products of combustion are conveyed to the chimney. The pipe J

communicates with the upper part of the stove, and also with the chamber I in the base of the same, as is clearly shown in fig. 1. A damper, i, is arranged in the upper part of the pipe J, to prevent the products of combustion from entering it from the top of the stove; and, when the damper is closed, the smoke will pass, through pipes K K, arranged on opposite sides of the stove, to the chamber I, heating the same, and will finally pass out through the pipe J.

To cause the full discharge of heat from the products of combustion while they are in the chamber I, an S-shaped partition, L, has been arranged vertically within the chamber I, as is shown more particularly in fig. 2, by means of which partition the smoke will be caused to pass from each pipe K, in the direction of the arrows in fig. 2, to the pipe J, this being the longest distance it can be guided from two pipes K, along the respective inner and outer walls of the chamber I, without breaking its current. The heat of the smoke will thus be fully utilized, for saving fuel, and for warming the fresh air that enters the room. By opening the damper i, the products of combustion will escape directly through the pipe J, without entering the pipes K and chambers I.

The channel E communicates with the chamber I by means of a perforation, j, in which a damper, k, is arranged, that can be closed or opened at will.

When the damper k is opened, fresh cold air will enter the chamber I, and will rise in the pipe L, for the purpose of checking the draught.

Having thus described my invention, what I claim as new, and desire to secure by Letters Patent, is—

1. The arrangement of the annular chamber E around the tubular downward extension C of the fire-box; said chamber communicating with the fire-box, and with the atmosphere in the room, so that a supply of fresh air, entering it, may be caused to enter the fire-box, and also the room, substantially as herein shown and described.

2. The chamber H, arranged in the bottom of the stove-base B, and close above the floor, and communicating with the draught-chamber E, as set forth, so that it will serve to distribute fresh warm air around the base of the stove, close above the floor, as specified.

3. The chambers E and H, when arranged as set forth, in combination with the chamber I, through which the products of combustion can be made to pass, so that thereby the fresh air passing through the chambers E and H will be warmed, substantially as herein shown and described.

4. The damper k, connecting the chambers E and I, for the purpose of allowing the introduction of fresh air from the draught-chamber E to the smoke-pipe J, substantially as herein shown and described, for the purpose of checking the draught.

5. The S-shaped partition L in the chamber I, in combination with the partition a, horizontal partition f, pipes K K, and smoke-pipe J, as herein described, for the purpose specified.

E. A. PARKER.
